UNITED STATES PATENT OFFICE.

WILLIAM J. WILLOUGHBY AND WILLIAM Y. ANDERSON, OF HORATIO,
ARKANSAS.

DESIGN FOR A CHURN-STAND.

SPECIFICATION forming part of Design No. 26,206, dated October 20, 1896.

Application filed September 9, 1896. Serial No. 605,332. Term of patent 14 years.

To all whom it may concern:

Be it known that we, WILLIAM J. WILLOUGHBY and WILLIAM Y. ANDERSON, citizens of the United States, residing at Horatio, 5 in the county of Sevier and State of Arkansas, have invented a new and original Design for Churn-Stands, of which the following is a specification.

This invention relates to a new and original 10 design for churn-stands; and it has for its object to provide a design of this character that shall be both useful and ornamental.

The leading feature of the design resides in a churn-stand having an inverted-V-shaped 15 upright frame provided with a pair of duplicate upwardly-converging standards joined together at their upper ends, and horizontal cross-pieces connecting the opposite standards, the front cross-pieces having semicircular indentations therein, a single leg-standard 20 arranged at the rear side of the inverted-V-shaped frame and having a lower rearwardly-inclined portion and an upper bowed or arched portion connected with said frame, 25 and a flat horizontal platform-piece connecting the converging frame-standards near their lower ends and provided with a curved indentation at its rear edge and forwardly-converging curved front edges. .

30 In the drawings, Figure 1 is a perspective view of a churn-stand embodying the herein-described design. Fig. 2 is a side elevation thereof. Fig. 3 is a rear elevation of the stand.

35 Referring to the drawings, 1 designates a churn-stand having an inverted-V-shaped frame 2, essentially comprising a pair of duplicate upwardly-converging standards 3,

joined together at their upper ends, as at 4, and provided above and below their centers 40 with chamfered edges 5. The inverted-V-shaped frame 2 is further provided at opposite sides thereof with horizontal cross-pieces 6, the front cross-pieces 6 having semicircular indentations or notches 7 in their front 45 edges. A single leg-standard 8 is arranged at the rear side of the frame 2, centrally between the standards 3 thereof and is fastened to the rear cross-pieces 6 of the frame. The said single rear leg-standard 8 is provided 50 with a lower rearwardly-inclined portion 9 and a bowed or arched upper portion 10, having a pair of parallel rearwardly-extending arm projections 11.

The lower terminals of the standards 3 and 55 8 are formed with the tapered feet 12, and the standards 3 are connected near their feet 12 by a flat horizontal platform-piece 13. The flat horizontal platform-piece 13 is provided with tapered ends 14, a curved indentation 15 at its rear edge, and forwardly-convergent curved front edges 16. The said platform-piece 13 is further provided at its outer front edge with a depending foot projection 17. 60

65 What we claim is—

The design for a churn-stand herein shown and described.

In testimony that we claim the foregoing as our own we have hereto affixed our signatures 70 in the presence of two witnesses.

WILLIAM J. WILLOUGHBY.

WILLIAM Y. ANDERSON.
